Attorney.

UNITED STATES PATENT OFFICE.

HENRY B. KEIPER, OF LANCASTER, PENNSYLVANIA.

TAP-WRENCH.

SPECIFICATION forming part of Letters Patent No. 595,312, dated December 14, 1897.

Application filed March 18, 1895. Serial No. 542,288. (No model.)

To all whom it may concern:

Be it known that I, HENRY B. KEIPER, a citizen of the United States, residing at Lancaster, in the county of Lancaster and State 5 of Pennsylvania, have invented certain new and useful Improvements in an Adjustable Tap-Wrench; and I do hereby declare the following to be a full, clear, and exact description of the invention, such as will enable 10 others skilled in the art to which it appertains to make and use the same.

This invention relates to improvements in that class of tools known to the trade as "adjustable tap-wrenches."

15 The object of the invention is the construction of a tap-wrench that may be expeditiously and conveniently adjusted to suit the heads of various sizes of taps arranged in sets or otherwise and in which each separate adjustment will adapt said wrench to hold the differently-sized heads of the same set from the largest to the smallest tap therein.

20 The elements of the invention, as well as the manner in which they perform their functions, will separately and collectively appear in the following description and will be clearly set forth in the claims.

25 The purposes of the invention are attained by mechanism and devices illustrated in the accompanying drawings, similar reference-letters designating like parts throughout the several views, in which—

30 Figure 1 is a side elevation of a tap-wrench embodying the elements of the invention, showing a collar-securing pin in dotted lines and a tap-head in place, with portions of each end of the handle cut out or broken away for want of room in the drawings; Fig. 2, an elevation similar to Fig. 1 with portions in longitudinal section taken through the center of said securing-pin, and a tap-head and a collar guide-pin in dotted lines, both in place; Fig. 3, a view similar to Fig. 2, but the section taken through the center of the collar 35 guide-pins, the collars some distance apart, and the retaining-pin cut away flush with the screw-threads of the central shaft; Fig. 4, a view from the right of Fig. 3, completed with the right-hand collar, the adjusting-nut, and 40 the tap-head removed; Fig. 5, a similar view from the left with the left-hand collar and securing-pin removed; Fig. 6, a view from the

right of Fig. 1 with the tap-head removed, and Fig. 7 a view from the left of the retaining-nut detached from Fig. 1.

55

As shown in the drawings, the tap-wrench of this invention comprises a central shaft A, two abutting collars A' A², and a retaining-nut A³ mounted thereon, with a pin a' fixedly securing one of said collars to said shaft. 60 The collars have in their abutting or adjacent faces a number of radial V-shaped recesses or indentations a⁴, of about ninety-degree openings and of varying depths, arranged in equal pairs and oppositely disposed, forming angular or square sockets about the periphery thereof, one-half of each socket being in each collar and the sockets adapted to hold tap-heads from the smallest to the largest in the several sets of taps, according to each separate adjustment, (see Fig. 1,) but the opposite pairs of said indentations are best shown in plan in Figs. 4 and 5.

65 The central shaft A is preferably a cylindrical bar or rod, of approved dimensions, 75 having a smooth central portion a, of increased diameter, provided at each end with screw-threads a² a³ and from beyond the screw-threads thinned or turned off to the depth of said threads and finished or polished 80 to the extremities of the shaft constituting the handle of the wrench.

70 Onto the threads a² of the shaft is screwed the outer end of the collar A', having its inner end for a prescribed distance on the 85 smooth central portion of the shaft and its outer end circumferentially thinned or turned off, as shown, and through which a pin a', likewise passing through the shaft, serves to securely hold said collar fixed in position to 90 said shaft. The collar A², likewise thinned at its outer end, is sleeved on the smooth portion of the shaft, movable back and forth thereon, while the screw A³ on the threads a³, screwed home onto said collar, serves to bind 95 the two collars together, holding them longitudinally in position, and pins a⁵ a⁵, having their rearward ends rigidly secured into the abutting face of one of the collars A' and their forward ends engaging corresponding holes 100 or sockets in the adjacent face of the other collar A², serve to guide said collar A² in lateral adjustment, as well as to keep it from turning or rotating on said shaft. A feather

a^6 (indicated by dotted lines in Figs. 3 and 5) is firmly seated lengthwise in the face of the shaft, and the inner face of the collar A^2 is provided with a corresponding groove a^7 (also indicated by dotted lines in the same figures) to be engaged by said feather to perform the same function—that is, guide said collar in adjustment or keep it from rotating. Either of these, the pins a^5 a^5 , with their sockets, or the feather a^6 , with its groove a^7 , may be omitted in the construction or both may be used without affecting the character of the invention.

An inspection of Figs. 1 and 2 shows how a tap-head is held in position in a socket, while an inspection of Figs. 2 and 3 shows a difference in lateral adjustment. It will here be observed that the pins a^5 of one collar should not be entirely withdrawn from their sockets of the other collar, this being particularly important when the feather and groove are omitted in the construction.

Having now particularly described my invention and set forth the manner in which it is performed, what I do consider new, and desire to secure by Letters Patent, is—

1. An adjustable tap-wrench comprising a cylindrical shaft with a smooth central portion having screw-threads at the ends thereof and of greater diameter than the rest of the shaft; abutting collars, with oppositely-disposed V-shaped indentations in their adjacent faces, mounted on said central portion, one collar with internal screw-threads engaging the threads on one end of said central portion and a pin passing through said collar and shaft and the other collar movable back and forth thereon with a key seated in the body of the shaft to engage a groove in the inner face of said movable collar, guide-pins secured in the abutting face of one collar to

engage corresponding sockets in the adjacent face of the other collar, and a nut engaging the threads on the adjacent end of said central portion, all substantially as described and for the purpose hereinbefore set forth. 45

2. The herein-described tap-wrench consisting of the shaft A with the smooth central portion a and the screw-threads a^2 a^3 on the ends thereof, the collar A' with the internal screw-threads engaging the threads a^2 and the pin a' passing through said collar and shaft, the collar A^2 movable back and forth on the central portion, and the nut A^3 in engagement with the threads a^3 , the V-shaped indentations a^4 in the adjacent faces of said abutting collars, and the pins a^5 a^5 secured into the abutting face of the one collar engaging corresponding sockets in the adjacent face of the other, all substantially as 60 and for the purpose set forth. 50

3. In an adjustable tap-wrench of the character described, in combination, the central shaft A having the central portion a with the threaded ends a^2 a^3 , the collar A' with the internal screw-threads on the threads a^2 and the pin a' passing through the collar and shaft, the collar A^2 sleeved on said central portion with the nut A^3 on the screw-threads a^3 ; the V-shaped indentations a^4 registering in pairs 65 in the adjacent faces of said collars, and the key a^6 seated in the body of the shaft and engaging the groove a^7 in the inner face of the collar A^2 all substantially as and for the purpose set forth. 70

In testimony whereof I affix my signature in presence of two witnesses.

HENRY B. KEIPER.
